UNITED STATES PATENT OFFICE.

JOSEPH M. STASSART, OF PORTLAND, OREGON, ASSIGNOR TO J. H. KEATING,
OF PORTLAND, OREGON.

NON-REFILLABLE BOTTLE.

No. 853,939.

Specification of Letters Patent.

Patented May 14, 1907.

Application filed June 6, 1906. Serial No. 320,483.

To all whom it may concern:

Be it known that I, JOSEPH M. STASSART, a citizen of the United States, residing at Portland, in the county of Multnomah and State of Oregon, have invented a new and useful Improvement in Non-Refillable Bottles, of which the following is a specification.

This invention relates to non-refillable bottles, the object being to provide a bottle which is very simple and cheap in construction, and one which is very effective in use.

Another object of my invention is to provide the bottle with a separate neck so that the valve can be readily put in place.

With these various objects in view, the invention consists in the employment of a bottle having a neck with an annular groove and outwardly extending lugs said neck carrying a valve, and a neck provided with an enlarged lower end having an annular groove and recesses adapted to be locked over said neck.

This invention consists of the novel features of construction, hereinafter fully described and pointed out in the claims.

In the drawings forming a part of this specification—Figure 1 is a vertical sectional view of the bottle partly broken away. Fig. 2 is a perspective view of the neck, the bottle being broken away. Fig. 3 is a perspective view of the separate neck partly broken away. Fig. 4 is a sectional view taken on the line 4—4 of Fig. 1. Fig. 5 is a sectional view taken on the line 5—5 of Fig. 1. Fig. 6 is a sectional view taken on the line 6—6 of Fig. 1. Fig. 7 is a perspective view of the guard. Fig. 8 is a perspective view of the guide-bar. Fig. 9 is a perspective view of the valve-seat. Fig. 10 is a perspective view of the valve.

In the drawing A, indicates a bottle of any desirable shape having a neck portion A', provided with an annular groove A², and oppositely disposed outwardly extending V-shaped lugs A³. An annular rib or shoulder A⁴, is formed on the lower end of the neck on which is arranged a ring B, having an inwardly projecting beveled edge flange B', forming a valve-seat B², in which the valve C, is adapted to be seated, the stem C', of which projects up through an opening formed in the cross-bar D, which is provided with reduced ends adapted to fit in the notches B³, formed in the upper edge of the ring B. A ball E, is

adapted to rest on the valve stem C', being held thereon by a cap F, provided with oppositely disposed outwardly extending arms F', adapted to rest on the upper edge of the neck, the outer ends of said arms being provided with upwardly extending lugs F².

A neck G, having an enlarged lower end G', provided with oppositely disposed V-shaped grooves G², and an annular recess G³, formed on the inside of said enlarged end, which is adapted to fit over the neck A', the V-shaped lugs A³, fitting in the V-shaped grooves G², which prevents the neck from turning. The shoulder G⁴, formed by the enlargement G', is adapted to rest on the lugs F², of the arm F', and securely hold the guard in place. A circular spring band H, is adapted to fit in the grooves A², and G², and securely lock the neck thereon so that it is impossible to remove the neck without breaking the bottle.

From the foregoing description, it will be readily seen that I have provided a bottle so constructed that the valve will be securely held in a vertical position but will unseat itself when turned down, so that the contents can pass out around the guard.

Having thus fully described my invention, what I claim as new and desire to secure by Letters Patent is:

1. In a device of the kind described, the combination with a bottle provided with a neck having an annular groove, of a valve arranged in said neck, a neck arranged over said neck provided with an annular groove, means for preventing the outer neck turning on the inner neck and a spring band adapted to fit in said grooves, and lock the neck thereon, for the purpose described.

2. In a device of the kind described, the combination with a bottle provided with an integral neck having an annular groove and lugs formed on said neck, a valve arranged in said neck, a guard arranged on the upper edge of said neck, a neck provided with an annular groove and recesses adapted to fit over said neck, and a spring band adapted to fit in the grooves of the necks, for the purpose described.

3. In a device of the kind described, the combination with a bottle having an integral neck provided with an annular rib, of a ring provided with a flange arranged on said rib, a valve seated on said flange, a bar arranged

over said valve on said ring, a ball arranged in said neck on said valve, a guard arranged on the upper edge of said neck, and a neck locked on said neck, for the purpose described.

4. In a device of the kind described, the combination with a bottle having a neck with an annular groove and oppositely disposed V-shaped lugs, of an annular shoulder formed on the lower end of said neck, a ring mounted on said shoulder provided with an inwardly projecting beveled edge flange, a valve mounted on said flange provided with a stem, a cross-bar arranged on said ring provided with an opening adapted to receive said stem, a guard arranged on the upper edge of said neck, and a neck provided with an enlarged lower end having an annular groove and oppositely disposed recesses, adapted to be locked on said neck, for the purpose described.

5. In a device of the kind described, the combination with a bottle provided with a neck portion having oppositely disposed lugs, of a valve arranged in said neck and a neck provided with oppositely disposed grooves adapted to fit over said neck and lugs, for the purpose described.

6. In a device of the kind described, the combination with a bottle provided with a

neck provided with oppositely disposed V-shaped lugs, of a valve arranged in said neck and a neck adapted to fit over said neck provided with oppositely disposed V-shaped grooves adapted to receive said lugs for the purpose described.

7. In a device of the kind described, the combination with a bottle provided with a neck having an annular groove and oppositely disposed lugs, of a valve arranged in said neck, a neck arranged over said neck provided with an annular groove and oppositely disposed grooves and a spring band adapted to fit in said annular grooves and lock the two necks together, for the purpose described.

8. In a device of the kind described, the combination with a bottle provided with a neck having an annular rib, of a ring provided with a beveled flange arranged on said rib, a stem valve mounted in said ring, an apertured bar arranged on said ring and over the stem of the valve, a ball arranged in said neck on the stem of the valve, a neck arranged on said neck and means for locking the necks together for the purpose described.
